Primary Examiner — Calvin E Vansant*Assistant Examiner* — Sydney M Evans(74) *Attorney, Agent, or Firm* — Sanchelima & Associates, P.A.; Jesus Sanchelima; Christian Sanchelima(57) **CLAIM**

The ornamental design for a manual trenching tool as shown and described.

DESCRIPTION

FIG. 1 is an isometric view of a manual trenching tool showing my new design;

FIG. 2 is a front elevational view thereof;

FIG. 3 is a top plan view thereof;

FIG. 4 is a bottom plan view thereof;

FIG. 5 is a right elevational view thereof;

FIG. 6 is a left side elevational view thereof; and,

FIG. 7 is a rear elevational view thereof showing my design. The broken lines in the drawings show features of the manual trenching tool that form no part of the claimed design.

1 Claim, 5 Drawing Sheets(56)
